UNITED STATES PATENT OFFICE.

JOHN JOSEPH O'DONNELL, OF AYLMER, CANADA.

TROLLEY-POLE CONTROLLER.

SPECIFICATION forming part of Letters Patent No. 731,606, dated June 23, 1903.

Application filed September 22, 1902. Serial No. 124,465. (No model.)

To all whom it may concern:

Be it known that I, JOHN JOSEPH O'DONNELL, electrician, of the village of Aylmer, in the county of Ottawa, Province of Quebec, 5 Canada, have invented certain new and useful Improvements in Trolley-Pole Controllers, of which the following is a specification.

My invention relates to improvements in controllers for trolley-poles; and the objects 10 of my invention are to provide a device which may be attached to the back of a trolley-car and which will serve to continually take up the slack of the trolley-cord, and, further, should the trolley-pole fly off the wires to immediately bring the trolley-pole down toward 15 the top of the car entirely clear of the cross-wires; and it consists, essentially, of a suitable casing having a central shaft, a pulley mounted on said shaft on which the trolley-cord is wound, said pulley being provided 20 with a suitable spring whereby it is caused to rotate and take up the slack of the trolley-cord, the said spring not being of sufficient strength to prevent the trolley-pole from following the unevennesses of the trolley-wire, 25 an emergency-spring being located in said casing and mechanism being provided between said pulley and said emergency-spring, whereby when the trolley-pole comes off the wire the sudden jerk given to the cord will 30 by centrifugal force cause the mechanism on the pulley to engage the mechanism attached to the side plates between which the emergency-spring is held, the effect being to release the said spring, which will wind up the trolley-cord on the pulley, thus drawing the trolley-pole down toward the top of the car, the various parts of the device being constructed and arranged in detail as hereinafter 35 more particularly described.

Figure 1 is a perspective view of the casing, part of which is broken away to show the interior parts, the pulley having been removed therefrom. Fig. 2 is a perspective view of 40 the pulley, showing the centrifugal clutch mechanism in its normal position and showing in dotted lines its position when caused to fly out. Fig. 3 is an elevation of the mechanism on one of the plates between which the 45 large spring is secured. Fig. 4 is a perspective view of the casing, showing a preferable

method of securing the same removably to the back of a car. Fig. 5 is a longitudinal elevation of the mechanism of the device, the casing having been removed. Fig. 6 is a view 55 of the end of the pulley, showing the spring which tends to keep the cord wound thereon. Fig. 7 is a detail of a portion of the large spring, showing a safety device for securing the same to the central shaft. 60

In the drawings like letters of reference indicate corresponding parts in each figure.

A is the casing, which is substantially cylindrical in form and is preferably cast with the end piece a integral therewith. 65

B is an end cover-plate for the end a' of the casing.

C is a central shaft, which extends throughout the length of the casing and is securely fastened by a nut b at the pulley end of the 70 casing and by suitable means at the emergency-spring end of the casing.

D is a pulley which is mounted on the shaft C.

The trolley-cord E (shown in dotted lines 75 in Fig. 5) passes through the hole a² in the casing A and is wound on the drum or pulley D. It is essential for the proper working of the device that the trolley-cord should be held taut all the time, and consequently a 80 spring F is provided within the circular wall d, formed on the side plate of the pulley. This spring is secured at one end to the stationary shaft C, and its other end is secured to a pin or post d', the said pin being firmly 85 secured to the side plate of the pulley. The spring F is made comparatively light, and it will thus be seen that as the trolley-pole follows the uneven portions of the trolley-wire the spring F will cause the pulley to wind up 90 the trolley-cord or allow the same to be unwound, as required.

G is a steel emergency-spring, which is located between the two plates H H', the said plates being firmly secured together by the 95 bolts h. The spring G is secured to the central stationary shaft C by suitable means; but the means which I prefer to employ are as follows: A collar g is secured to the shaft C by means of a set-screw g' or other suitable 100 fastening device. A slot g² extends into the collar g, and in this slot a slidible plunger g³

is located. A spring g^4 is placed in the slot g^2 and is designed to force the plunger g^3 outwardly. A longitudinal slot g^5 is formed in proximity to the inner end of the spring G , 5 and the plunger g^3 is designed to extend through this slot. The face of the plunger in proximity to the end of the spring is flat, but the rear face g^6 is beveled. It will thus be seen that should anything happen that would 10 permit the spring G to very rapidly unwind the plunger g^3 would be forced back into the slot, thus permitting the ends of the spring to turn loosely, and accident would thus be avoided. The outer end of the spring G is 15 secured to one of the bolts h in a suitable manner.

a^3 represents stops, which are either cast on the inner periphery of the casing or are secured thereto.

20 A latch I is slidably held in a groove h' , formed in the side plate H . This latch is forced upwardly by a suitable spring i , which is secured to a projection h^2 from the side plate H . The forward face i' of the said 25 latch is designed to engage one of the stops a^3 , and thus it will be seen that when the spring G is wound up it will be prevented from unwinding by the said latch.

I will now proceed to describe the mechanism on the side plate H and on the side plate d^2 of the pulley D whereby when a sudden jerk comes on the trolley-rope the mechanism on the pulley will release the latch I and at the same time engage the mechanism of the 35 side plate H , thus allowing the spring G to rapidly turn the whole interior mechanism of the device, the result being that the trolley-cord will wind onto the pulley D , and thus the trolley-pole will almost immediately be pulled 40 down below the level of the cross-wires, so that all damage will be prevented.

The latch I is provided with two projections i^2 i^3 . A lever J is pivotally secured to the plate H by a suitable pin or pivot j . This 45 lever passes between the projections i^2 and i^3 and curves downwardly in such a way as to approximately follow the curve of the circumference of the side plate H . A stop h^3 is formed on or secured to the side plate H , and 50 the lever J abuts this stop, and thus prevents the spring i from forcing the latch I out farther than it is necessary for it go. A projection j' is formed at or near the end of the lever J and extends toward the pulley D .

55 K is a lever, which is pivotally secured near the center of the side plate H . A suitable spring k tends to force the free end of the lever K toward the circumference of the side plate H . At the free end of the lever K 60 a projection k' is formed, which extends toward the pulley D . A stop k^2 is formed on or secured to the side plate H and is designed to limit the motion or swing of the lever K in the downward direction for reasons to be 65 hereinafter pointed out.

The lower portion of the latch I is provided with a notch i^4 on one side, and the por-

tion of the latch below the said notch is beveled off.

70 L is a bell-crank lever comprising the substantially upright portion l and the substantially horizontal portion l' . A pivot l^2 pivotally secures the said bell-crank lever to the side plate H . The upper end of the upright portion l is provided with a downwardly- 75 sloping point or tooth l^3 , and the upper surface l^4 of the said tooth is curved or beveled, as shown.

80 M is a release-bar pivotally secured by the bolt or pivot m to the side plate H . The end m' of this bar extends normally beyond the circumference of the side plate H , and one side, m^2 , of the said bar is designed to engage the stops a^3 . The other side, m^3 , is beveled or curved, so as to slide over the said stops. 85

l^5 is a spring, which is secured to the side plate H by any suitable means and is designed to press upwardly against the lower side of the bell-crank lever L .

90 Referring to Fig. 1, it will now be seen that if the lever J be pulled downwardly in the direction indicated by the arrow the latch I will be drawn down out of engagement with the stops a^3 and the beveled face beneath the notch i^4 will come in contact with the beveled 95 face l^4 of the bell-crank lever and they will slip over each other till the tooth l^3 snaps into and engages the notch i^4 , and thus the latch I will be held in the lower position until such time as the bell-crank lever is caused by the 100 bar M to swing back and release the latch. The mechanism on the pulley by means of which these various operations are performed I will now proceed to describe.

105 N and N' are the two centrifugal clutch-bars, which are pivoted at n and n' between the brackets O O' and the side plate d^2 of the pulley D . A rocking lever P is provided and is rotatably mounted on the central shaft C . Connecting rods or links Q Q' are secured to 110 the ends of the double lever P , and at their opposite ends they are pivotally secured to the bars N and N' . A spiral spring R is provided and is secured at one end to the end of one of the bars N N' by suitable means. The 115 opposite end of the said spring may be directly secured to the side plate d^2 , but in order to permit of its being adjusted I prefer to attach its end to one end of a lever r , the other end of the said lever being in contact with the 120 end of a set-screw r' , which extends through a projection r^2 , formed on the side plate d^2 . By means of this set-screw the tension of the 125 spring R may be regulated. During the ordinary running of the car the trolley-cord and the spring F will cause the pulley to rotate backward and forward at a fairly even and regular rate of speed, but when a sudden jerk or pull comes on the trolley-cord the pulley will be caused to rotate very quickly, 130 the result being that the bars N N' , through centrifugal force, will be caused to fly out in spite of the pull of the spring R into the positions shown in dotted lines in Fig. 2. The

side plate d^2 has stops d^3 and d^4 formed thereon to prevent the said bars from swinging too far.

n^2 and n^3 are cams, which are formed on the bars N N' . Under ordinary circumstances the position of the mechanism on the side plate H is as shown in Fig. 1, and the mechanism on the side plate d^2 of the pulley D is in the position shown in full in Fig. 2; but when, as above described, the bars N N' fly out into the position shown in dotted lines in Fig. 2 either one or other of the cams n^2 n^3 will engage the projections j' and k' on the levers J and K , respectively. As the pulley D continues to revolve the cam which has engaged the projections j' and k' will draw the levers J and K down to the positions shown in Fig. 3, and it will be seen that in this position the latch I is engaged by the bell-crank lever L , so that the spring G is now free to act in rotating the entire mechanism in the direction indicated by the arrow in Fig. 3. The entire mechanism, including the pulley D , will now be rapidly turned by the emergency-spring G until the trolley-pole has been drawn down such a distance that the strength of its springs will counteract the effect of the spring G and the trolley-pole will come to rest. In order to replace the trolley-pole, the conductor on the car has only to pull upwardly on the trolley-cord, the effect of this pull being first to rotate the entire mechanism of the device in the direction opposite to the direction indicated by the arrow. The releasing-bar M will engage the first one of the stops a^3 which it comes to and, pressing against the bell-crank lever L , will cause the latch I to be released, and the said latch will immediately spring back to its normal position, as shown in Fig. 1. The pin or projection j' on the lever J , it may here be observed, slips over the end of the cam n^2 just at the moment when the tooth t^3 has engaged the notch i^4 . (See Fig. 3.) So it will be seen that the lever J will not be prevented from flying back when the latch is released; but the projection k' on the lever K is still held by the cam, and it is by means of the contact between these two parts that the spring G rotates the pulley. The curved face i^5 of the latch I will slide over the stops a^3 while the spring is being wound up by the conductor pulling on the trolley-rope, and as soon as the spring has been sufficiently wound up the conductor will slacken the rope, thus allowing the cam n^2 on the centrifugal clutch or bar N to slide clear of the projection k' , so that the bars N N' will return to their normal position, as shown in Fig. 2, owing to the pull of the spring R , and the swinging bar K will return to its normal position, owing to the pressure of the spring k . The operation will now commence as before, and the trolley-cord will wind and unwind until a sharp pull takes place, when the previously-described operation will be repeated.

It will now be seen that I have invented a

device which will overcome a difficulty which in the past has been the cause of considerable loss of time and money to electric railways and has been a source of annoyance to conductors and passengers.

A variety of means might be employed for securing this device to the car and it might also be secured in a number of different places which would be convenient under various circumstances. I prefer, however, to secure the machine to the rear portion of the car, and for this purpose I provide a plate S , having grooves s formed therein. This plate is designed to be secured to the back of the car, and tongues a^4 , which are formed on the casing, are adapted to slide into the said grooves, thereby holding the machine in place. A plate, such as S , may be attached to both ends of a car if the car has to be reversed, so that the device may be secured to the end of the trolley-car at which the pole is being used.

In the construction of my device for practical purposes it will be understood that a great many variations in the details of the mechanism may be made without departing from the spirit of my invention, although the forms of the various parts shown in the drawings are found to work satisfactorily. For example, instead of using two centrifugal clutch-arms N and N' , as shown, it might be preferable to only use one in order to make a slight reduction in the cost of the device, though of course it would not act as quickly as when two clutches are used. Various forms of stops for limiting the motion of the swinging arms might also be used, the forms shown in the drawings being taken for purposes of illustration only. Changes might also be made in the form of the frame or casing; but as all such changes come within the scope of my invention they need not be here described in detail.

What I claim as my invention is—

1. In a device of the class described a suitable frame or casing, a stationary supporting-shaft therein, a winding-drum for the trolley-cord mounted on said shaft, a spring acting on said drum to cause it to take up the slack of the trolley-cord, a pair of connected plates journaled on said shaft, an emergency-spring having one end fixed and the other end connected with the plates, a spring-actuated bolt or latch slidably carried by the plate adjacent the winding-drum, said bolt being normally held with its end projecting normally beyond the disk, a stop on the frame or casing designed to engage the end of said bolt, means carried by the drum for withdrawing the latch to allow the emergency-spring to rotate the plates when said drum is suddenly rotated and means for causing the rotation of the plates to rotate the drum to wind up the trolley-cord, substantially as described.

2. In a device of the class described a suitable frame or casing, a stationary supporting-

- shaft therein, a winding-drum for the trolley-cord mounted on said shaft, a spring acting on said drum to cause it to take up the slack of the trolley-cord, a pair of connected plates journaled on said shaft, an emergency-spring having one end fixed and the other end connected with the plates, a spring-actuated bolt or latch slidably carried by the plate adjacent the winding-drum, said bolt being normally held with its end projecting normally beyond the disk, a stop on the frame or casing designed to engage the end of said bolt, centrifugal-controlled means carried by the drum for withdrawing the bolt when the drum is suddenly rotated to allow the emergency-spring to rotate said plates and means for connecting said plates with the drum to wind up the trolley-cord, substantially as described.
- 20 3. In combination the frame or casing having a stationary shaft, trolley-cord-winding drum journaled thereon, a spring acting on said drum to take up the slack of the cord, a pair of connected plates journaled on said shaft, an emergency-spring acting on said plates, a bolt carried by one of said plates adapted to project normally outward, a projection carried by said casing designed to engage said bolt, a lever-arm for operating said latch, a projection supported from one of the plates and centrifugal arms carried by the drum adapted on sudden rotation of said drum to shift said lever-arm and engage said projection, substantially as described.
- 25 4. In combination, the frame or casing having a stationary shaft, a trolley-cord-winding drum journaled on said shaft, a spring acting on said drum, a plate journaled on said shaft, adjacent the drum, an emergency-spring tending to rotate said plate, a bolt radially movable of the plate, a projection on the casing adapted to be engaged by said bolt, a lever-arm for retracting said bolt, a locking-lever for holding the same retracted, centrifugal arms carried by the drum adapted when the same is suddenly rotated to operate said lever-arm to retract the bolt and operatively connect the said plate with the drum, and means for operating the locking-lever to release the latch, substantially as described.
- 30 5. In combination, the frame or casing having a stationary shaft, a trolley-cord-winding drum journaled on said shaft, a spring acting on said drum, a plate journaled on said shaft, adjacent the drum, an emergency-spring tending to rotate said plate, a bolt radially movable of the plate, a projection on the casing adapted to be engaged by said bolt, a lever-arm for retracting said bolt, a locking-lever for holding the same retracted, centrifugal arms carried by the drum adapted when the same is suddenly rotated to operate said lever-arm to retract the bolt and operatively connect the said plate with the drum, and means for operating the locking-lever to release the latch, said means comprising a pivoted bar

extending into the path of the projection on the casing and adapted to contact with said locking-lever, substantially as described.

6. In combination, a cylindrical casing, the spring-controlled pulley or drum rotatably mounted in said casing and the emergency-spring located between a pair of rotatably-mounted disks or plates, of a spring-actuated bolt slidably held in a slot in the disk nearest to the said pulley, said bolt being held normally with its end projecting beyond the circumference of said disk, stops on the inside of said casing adapted to engage said bolt whereby the rotation of said disks is prevented, a releasing-arm pivoted at one end to said disk and extending between a pair of projections on said bolt or latch, an engaging arm pivoted at one end in proximity to the center of said disk, a spring tending to force the free end of the said engaging arm to the circumference of the disk, said releasing-arm and said engaging arm each being provided with a projection extending toward said pulley, a stop for limiting the swing of said engaging arm in the inward direction, a centrifugal clutch on the inner or adjacent face of said pulley adapted to engage the projections on said arms when the pulley is rapidly rotated thus drawing in the said bolt or latch and releasing the emergency-spring, a retaining means for said bolt or latch designed to hold the same from operative engagement with the stops while the emergency-spring is unwinding and means for causing said retaining means to disengage said bolt or latch as soon as rewinding of the emergency-spring is commenced as and for the purpose specified.

7. In a centrifugal clutch for a device of the class described the combination with a pulley and the stationary shaft, of a pair of bars pivotally secured to the face of said pulley at one of their ends, said bars being symmetrically disposed on each side of the shaft, a double lever mounted on the said shaft, a pair of links an end of each being pivoted one to one end and the other to the other end of said double lever, the opposite ends thereof being pivoted to said swinging bars, a spring secured to one of said swinging bars and means for adjusting the tension of said spring as and for the purpose specified.

8. In a device of the class described the combination with the disk or plate the spring-actuated latch or bolt and the means for withdrawing it from engagement with the stops, of a substantially L-shaped or bell-crank lever pivotally secured to the said disk, means at one end of said lever for engaging the lower end of said bolt or latch, a spring designed to hold said lever in engagement with said latch, a releasing-bar pivotally secured to the said disk or plate and adapted to engage the stops on the inner circumference of the casing thereby causing said L-shaped lever to disengage the bolt or latch as and for the purpose specified.

9. In a device of the class described the

combination with the emergency-spring and the rotatable disks or plates between which it is located and to which it is suitably secured at its outer end, of a collar secured to the stationary shaft and having an inwardly-extending slot or recess formed in the circumference of said collar, a bolt located in said slot, a spring between the end of said bolt and the end of the slot, the outer end of

said bolt being beveled and designed to engage a slot formed in the end of said emergency-spring as and for the purpose specified.

Signed at Ottawa this 15th day of September, 1902.

JOHN JOSEPH O'DONNELL.
